NURSE'S CAP

Delabian J. Rice, Montclair, N.J., assignor to Alumnae
Association of Harlem Hospital School of Nursing,
New York, N.Y., a corporation of New York

Application August 3, 1959, Serial No. 57,038

Term of patent 14 years

(Cl. D3—13)

FIG. 1

FIG. 2

FIG. 3

FIG. 4

FIG. 5

Fig. 1 is a side perspective view of a nurse's cap, showing my new design;

Fig. 2 is a top plan view, to a reduced scale;

Fig. 3 is a back elevational view, to a reduced scale;

Fig. 4 is a side elevational view, to a reduced scale; and

Fig. 5 is a front elevational view, to a reduced scale.

I claim:

The ornamental design for a nurse's cap, as shown.
